UNITED STATES PATENT OFFICE.

ROBERT SHORTS, OF SAN JOSE, COSTA RICA.

STARCH AND VEGETABLE-OIL EXTRACTING MACHINE.

Application filed November 29, 1922. Serial No. 603,909.

To all whom it may concern:

Be it known that I, ROBERT SHORTS, a British subject (Canadian), resident of the city of San Jose, in the Republic of Costa Rica, have invented a new and useful Improvement in Starch and Vegetable-Oil Extracting Machines, of which the following is a specification.

The object of my invention is to provide 10 a device to facilitate the extraction of starch from yucca (cassava) and other starch bearing tubers, also to facilitate the extraction of oil from cocoanuts and other oil bearing nuts. The object is accomplished by first 15 reducing the starch bearing tubers and the oil bearing nuts to a pulp and then by draining off by various processes the starch or oil substance from the pulp.

From observation and experiment with 20 machines for making starch, I have learned that when the starch bearing tubers are being ground on a grating wheel that is flushed with water, the resulting product is in the form of scrapings rather than meal, 25 that the force required to scrape the tubers breaks up their cellular tissues and literally squeezes the juice out of them into the water (that is on the wheel) which immediately takes it up and holds it in a milk like 30 solution. Likewise, I have observed that the instant the scrapings are released from the wheel a reaction takes place in them and there is a tendency to absorb back as much liquid as has been squeezed out of them. 35 Therefore, the slightest delay in separating the milky water from the meal, or scrapings, is detrimental. My invention provides a means for preventing the absorption by the scrapings, of the starch that has been 40 squeezed out of them. This is accomplished by instantly straining the pulp in the manner and by use of the means herein described.

Referring to the accompanying drawings, Fig. 1 is a side elevation of the machine.

Fig. 2 is a top plan view of the machine.

Fig. 3 is a longitudinal section of it taken on the line 3—3 Fig. 5.

Fig. 4 is a sectional plan view showing 50 particularly the strainer and is taken on the line 4—4 of Fig. 3.

Fig. 5 is an end elevation of the machine.

Fig. 6 is a cross-sectional view taken on the line 6—6 of Fig. 1.

Fig. 7 is a fragmentary sectional view.

More particularly *a* represents a grating 55 wheel with an axle running through the cen-

ter mounted on a frame and having an arm or lever attached to the axle for the purpose of revolving it. The upper portion of the wheel is enclosed in a hopper, *b*, in which the tubers (or the nuts) are placed when about to be ground on the wheel. Inside of the hopper, but independent of it, is a feed bar, or compressor, *c*, which is hinged at the back of the machine, *d*, and is intended 60 to move freely up and down in the hopper on the roots, holding them against the grating wheel and exerting the pressure of its own weight to which is added the pressure of an adjustable spring, *e*, situated at the 65 lower end of the feed bar. The bar is tangent to the face of the wheel. Thus, when the tuber (or the nut) is fed on to the face of the wheel, through the hopper, it is carried forward as the grating wheel is 70 revolved clockwise until it is stopped by a bridge in the hopper across the face of the wheel. At the same time the feed bar rises 75 to receive it and presses it against the grater until it is entirely reduced to fine meal, or 80 scrapings. During this process the surface of the grinding wheel is flushed with pure water supplied as follows: A tank, *f*, is located on the top of the frame (or elsewhere), 85 and by means of a control valve, *g*, and a tube, *h*, leading out of the tank, the water may be conveyed from the tank to a small auxiliary tank or sprinkling box, *i*, located near enough to the grinding wheel to sprinkle its surface with water. The sprinkling 90 box has two outlets, consisting of small holes extending in two lines crosswise to the machine; one outlet is in the end of the box, the water passing through which flushes the 95 surface of the grinding wheel, and through the other outlet water pours down upon a strainer as indicated in Fig. 3 for the purpose of giving the pulp a final washing. The main object of the sprinkling box, as a 100 whole, is to enable the operator to supply the machine at the earliest possible moment after grinding with the requisite quantity of water to insure the effectual washing of the starch out of the meal.

When the water from the sprinkling box 105 flushes the grinding wheel, which is already thinly covered with the semiliquid pulp, this supply of water added to that already in the pulp contributes to the cleansing of the pulp and completes the first process of 110 washing the starch out of the meal. Then after the wheel revolves further, the whole

milk like semiliquid mass is thrown off on to the upper end of an inclined vibrating double strainer, *k*, which is situated lower down on the frame and is in a position to 5 receive the falling pulp. Most of the water drains out of the meal immediately. The strainer, with its housing, in dimension corresponds approximately with the inside measurements of the frame of the machine, 10 and is secured to the frame at an incline, the upper end of it being just below the bottom of the wheel, so as to receive the whole discharge from the wheel. The strainer is of special construction and is in fact two 15 long narrow strainers in one, one being immediately above the other about one and one-half inches apart. It is in effect a double suspension strainer, the slight deflection of which provides a kind of shallow trough, down which the meal travels under a shower of water from the sprinkling box aided by a succession of violent jolts, produced by means hereinafter described, until the meal reaches the lower 20 end of the strainer where it falls off. Meanwhile the milky water which passes through the two strainers falls on to a dripboard, *l*, which receives it and conveys it to the discharge spout, *m*, from which it may be 25 passed on to a settling tank not shown in the drawings. The strainer, *k*, consists of a fine cotton cloth (or any suitable fabric) doubled and joined together at the edges like a pillow case, and drawn somewhat 30 tightly over a shallow skeleton frame, *n*, no nails or tacks being required to fasten it to the frame. After the strainer cloth is 35 stretched over the frame, a housing, *o*, is fastened to both edges by screws in such a manner as to project a little beyond the edges and 40 beyond each end of the frame as a protection for the delicate strainer cloth. The lower edges of the housing rest on the dripboard, *l*, taking the weight and wear off the cloth and 45 providing a space between the frame and the dripboard, *l*, for the cloth to hang in suspension from the edges throughout its entire length. The top half of the strainer cloth, it may be observed, also hangs suspended in the same manner from the top 50 edge of the frame, thus producing what I call the suspension double strainer. As the strainer is separate from all the parts of the machine, it can easily be removed or 55 slipped back into position where it automatically locks itself by means of a notch, *p*, on the bottom edge of the housing near its lower end and by a check block, *q*, attached to the dripboard. The housing of 60 the strainer, *k*, extends a little beyond the discharge spout, *m*, and the cloth of the strainer being made a foot or so longer drops down as a curtain outside of the discharge spout, *m*, and so prevents any of the 65 waste from getting into the discharge spout

and damaging the starch. While the greater portion of the water falling down on to the upper strainer passes almost immediately to the lower one and through this to the dripboard, the lighter drippings having a tendency to cling to the under-side of both strainers and to pass off with the waste. To prevent this a narrow strip of cloth, *r*, about an inch wide is sewn on to the bottom sides of both strainers near the lower end just over the center of the discharge spout, *m*, something like the flounce on a dress, and allowed to hang down. These flounces, or strips of cloth, obstruct the passage of the drippings and divert them into the discharge spout with the rest of the milky water. Beneath the strainer is the dripboard, *l*; it is the same width as the strainer but not quite as long. The strainer, *k*, rests on its housing on the top of the drip-board, and, being a little longer than this drip-board, overhangs it at the lower end. The dripboard is set at the same incline as the strainer, immediately under it and flush with the front end of the machine. It is suspended on hinged stirrups, *s*, and caused to vibrate endwise rapidly by means of a right angle rod, *t*, pivoted at its angle. The lower end of this rod is attached to a lug, *u*, on the dripboard, *l*, and the other end of the rod comes in broken contact with a series of pins, *v*, spaced on a circle on the side of the grinding wheel and near its center. Thus as the grinding wheel is turned, the lower end of the rod is forced outwardly and the dripboard is carried outwardly by it. This compresses a spring, *w*, that rests against a cleat, *x*, on the bottom side of the dripboard and against a board, *y*, across the front of the machine. When the forward movement of the grinding wheel breaks contact with the contiguous end of the right angle rod, *t*, the spring, *w*, reacts on the dripboard, together with the strainer that rests on top of it, and both strainer and dripboard shoot back against the rear end of the frame, causing a jolt that shakes up and loosens the pulp on the strainer, thereby making easier the washing out of the starch.

The object of the dripboard is to receive the water that passes through the strainer and to convey it to the discharge spout, *m*, from which the water is received into a settling tank not shown in the drawings. After the starch is settled and the water in the tank has been drawn off, a byproduct will be found lying loosely on the surface of the starch in those cases in which the thick bark, or skin, has not been removed from the tubers before grinding. This product of the bark must be removed in order to obtain pure starch, and it can easily be done without disturbing the starch by means of a soft brush or by gently flushing

it off with water. This done, the starch will be found in a glistening white mass on the bottom. The process of extracting oil from cocoanuts and other oil bearing nuts is the same as that for making starch, until the milky water is discharged into the settling tank. At this point the process differs in that the oily substance gradually separates from the water and rises like bubbles to the top, forming a thick cream which can be skimmed off and, when brought to a boiling heat, is transformed from a cream into the highest quality of transparent cocoanut oil, leaving as a sediment a very small residue of scrapings or waste.

Having thus described my invention, what I now claim as new and desire to protect by Letters Patent is as follows:

1. In a device of the character described, the combination of a hopper for receiving the material to be ground, means for grinding the material, a strainer positioned below the grinding wheel to receive the material after being ground, and a tank so positioned as to simultaneously supply water through its side to the material immediately after being ground and through its bottom to the material while being strained.
2. In a device of the character described, the combination of a hopper for receiving the material to be ground, means for grinding the material, a strainer positioned below the grinding wheel to receive the material after being ground, and a tank positioned

above the axis of the grinding wheel and adjacent said wheel, said tank supplying water through a side wall to the material immediately after being ground and through its bottom wall to the material while being strained.

3. In a device of the character described, the combination of a hopper for receiving the material to be ground, means for grinding the material, a strainer positioned below the grinding wheel to receive the material after being ground, means for vibrating the strainer and a tank positioned adjacent the grinding wheel, said tank supplying water through a side wall to the material immediately after being ground and through its lower wall to the material while being strained.

4. In a device of the character described, the combination of a grinding wheel for grinding the material, an inclined strainer located under and below the grinding wheel, a tank located above the axis of the grinding wheel and adjacent the periphery thereof, perforations in the side of the tank adjacent the grinding wheel for supplying water to the material immediately after being ground and perforations in the bottom of the tank to supply water while the material is being strained.

This specification signed the 17th of November, 1922.

ROBERT SHORTS.
